United States Patent Office

Des. 220,897
Patented June 15, 1971

220,897

BRASSIERE

Raymond Pioli, Floral Park, N.Y., assignor to Maidenform, Inc., New York, N.Y.

Filed Sept. 12, 1969, Ser. No. 19,133

Term of patent 7 years

Int. Cl. D2—02

U.S. Cl. D2—24

The figure is a front perspective view of a brassiere showing my new design, the rear face being conventional.

I claim:

The ornamental design for a brassiere, substantially as shown and described.
